Primary Examiner — Robin V Webster(74) *Attorney, Agent, or Firm* — Renner, Otto, Boisselle & Sklar, LLP**CLAIM**

The ornamental design for a spray gun nozzle, as shown and described.

DESCRIPTION

FIG. 1 is a front perspective view of a spray gun nozzle showing my new design with the nozzle ring in the retracted position.

FIG. 2 is rear perspective view thereof.

FIG. 3 is a right side view thereof, a left side view being a mirror image thereof.

FIG. 4 is a top view thereof, a bottom view being a mirror image thereof.

FIG. 5 is a rear view thereof.

FIG. 6 is a front view thereof.

FIG. 7 is an alternate front perspective view of the spray gun nozzle with the nozzle ring in the forward position.

FIG. 8 is rear perspective view thereof.

FIG. 9 is a right side view thereof, a left side view being a mirror image thereof; and,

FIG. 10 is a top view thereof, a bottom view being a mirror image thereof.

Rear and front views of the spray gun nozzle with the nozzle ring in the forward position are omitted as they would be identical to FIGS. 5 and 6, respectively.
